UNITED STATES PATENT OFFICE.

J. C. HERMAN TROST, OF BROOKLYN, NEW YORK.

DESIGN FOR A DISH.

SPECIFICATION forming part of Design No. 12,317, dated June 14, 1881.

Application filed April 22, 1881. Term of patent 7 years.

To all whom it may concern:

Be it known that I, J. C. HERMAN TROST, of Brooklyn, in the county of Kings and State of New York, have invented a new Design for Dishes, of which the following is a specification.

Figure 1 is a sectional side elevation of a dish, illustrating my new design. Fig. 2 is a sectional end elevation of the same.

Similar letters of reference indicate corresponding parts.

The leading features of my design consist in forming the bodies of the dishes with an upward, outward, inward, and outward curve, and also in forming the handles of the dishes and covers of two studs connected at their outer ends by a bar.

A represents the flange or foot upon which the dish stands.

B is the bottom of the dish, which is nearly flat. From the bottom B of the dish, at or near its intersection with the foot A, the walls C of the said dish curve upward, outward, inward, and outward, making the lower part of the body longer and wider than the upper part, and giving a flare to the rim of the dish, as shown in Figs. 1 and 2. The cover D is convexed in the ordinary manner.

The handles are each formed of two studs, E, connected at their outer ends by a bar, F.

The studs E incline from each other, and the ends of the connecting-bar F project beyond the said studs. The handle E F has a bead around the outer and inner edges of its sides.

Having thus fully described my invention, I claim as new and desire to secure by Design Patent—

1. The design for a dish herein shown and described, the same consisting of the walls of the dish-body curved upward, outward, inward, and outward, making the lower part of the dish-body longer and wider than the upper part, and giving a flare to the rim of the dish, as set forth.

2. The design for the dish-handle herein shown and described, the same consisting of two inclined studs connected at their outer ends by a bar, with the ends of the bar projecting beyond the studs, and with beads extending along the outer and inner edges of the sides of the said handle, as set forth.

J. C. HERMAN TROST.
